CLAIM

The ornamental design for a light filter for a cell phone as shown and described.

DESCRIPTION

FIG. 1 is a front perspective view showing the light filter for a cell phone, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front perspective view showing the light filter for a cell phone in a state of use on environment.

The broken lines shown in the figures depict portions of the light filter for a cell phone that form no part of the claimed design. The additional broken draft lines only seen in FIG. 8 depict environment and form no part of the claimed design.

1 Claim, 4 Drawing Sheets
